UNITED STATES PATENT OFFICE.

JOHN SNELL CHENHALLS, OF PLYMOUTH, ENGLAND, ASSIGNOR TO ROBERT J. AKERS, OF GLENROSA VALE, WOLDINGHAM, SURREY, ENGLAND.

STEAM-GENERATOR.

SPECIFICATION forming part of Letters Patent No. 737,346, dated August 25, 1903.

Application filed February 13, 1902. Serial No. 93,818. (No model.)

To all whom it may concern:

Be it known that I, JOHN SNELL CHENHALLS, engineer, of 59 Ebrington street, Plymouth, in the county of Devon, England, have invented a certain new and useful Improvement in Steam-Generators, of which the following is a full, clear, and exact description, and for which I have applied for Letters Patent in Great Britain, No. 15,059, dated July 24, 1901.

My invention consists of an improved steam-generator of the type known as "flash" steam-generators in which I employ a tube in a continuous coil surrounding an oil or spirit burner and forming its casing, in conjunction with a steam-receiver, which also acts as a superheater for the steam generated in the coiled tube.

The invention is illustrated upon the accompanying drawings, upon which—

Figure 1 is a longitudinal section, and Fig. 2 is a cross-section of the same. Fig. 3 is an elevation, on an enlarged scale, of one of the distance-pieces arranged upon a tube.

I provide a continuous pipe *a*, arranged in a coil, and the coil after being continued to the end of the casing *b* is returned within or around itself two or more times, forming other coils concentric with the first. The pipe *a*, which is preferably of uniform bore, finishes in an arm *c*, delivering to a pipe *d* of larger diameter, which is in turn arranged within the casing as a coil around the coils *a*. The other end of coil *d* is provided with an ordinary stop-valve. (Not shown.) At intervals around the coils *a* are arranged upon the pipes *a* a number of short distance-pieces *e*, which are made as flanged-ferrules, having perforations *f* in the flanges. These distance-pieces are made of fire-clay or other refractory material, and they serve to keep the adjacent tubes apart and to break up the heated gases during their passage between the coils.

The ferrules are cut away at *e'* to allow the heated gases free access to the tubes. The distance-pieces are preferably arranged as

shown in Fig. 3, the ferrules abutting against one another.

The burner employed to heat the water may be an oil or spirit burner of any ordinary construction, and it is arranged within the coils *a*, a space being shown left for the purpose, although the burner need not be shown. The casing *b* is preferably formed as a double wall containing asbestos or similar non-conducting material.

The diameters of the pipes *a* and *d* are proportioned one to the other. A suitable proportion is one to four; but any sizes and proportions may be used.

Feed-water is injected under pressure into the outer end of the coiled tube *a* and is flashed into steam as it passes through the heated coiled tube. The steam thus formed passes into the outer receiver *d*. A suitable check-valve is arranged upon the exterior of this tube *a* to control the supply of feed-water.

To the outside of the casing *b* is attached a chamber *h*, to which is secured a chimney *i*, and within the chamber *h* is arranged a coil *g*, through which the exhaust from the engine is caused to pass before entering the chimney and escaping to the atmosphere. By this means the immediate condensation of the exhaust-steam is avoided, and it leaves the chimney in the form of superheated vapor.

Having thus described my invention, what I claim as such, and desire to secure by Letters Patent, is—

1. A flash-boiler comprising an inner coil in which the feed-water is flashed into steam, an outer larger coil arranged around said inner coil and acting as a steam-receiver and superheater, and an arm exterior to said coils connecting said outer superheating boiler-coil directly to said inner generating boiler-coil.

2. A flash-boiler comprising an inner generating-coil in which the feed-water is flashed into steam, an outer larger superheating-coil

enveloping said inner coil, an arm directly connecting said outer coil to said inner coil, and a jacketed casing within which said coils are located, said connecting-arm between the 5 boiler-coils being outside the casing.

3. A flash-boiler comprising an inner coil, an outer larger coil arranged around said inner coil, an arm connecting said outer coil to said inner coil, ferrules of refractory material

upon said coils, flanges to said ferrules, and 10 perforations in said flanges and ferrules.

In witness whereof I have hereunto set my hand in presence of two witnesses.

JOHN SNELL CHENHALLS.
